RAIL TURNING DEVICE

Gustaf Westerholm, Hobart, Ind., assignor to Carnegie-Illinois Steel Corporation, a corporation of New Jersey

Application October 25, 1945, Serial No. 624,402

11 Claims. (Cl. 214—1)

1

This invention relates to a rail turning device and more particularly to such a device for turning the rails from a position with the head up to a position on their sides. During the process of manufacture, the rails are inspected at various stages and in order to inspect the rails they must be turned from a position with the head up to a position on their sides. The first inspection of the rails after they have been slow cooled is at the inspection and transfer bed just after the rails have been unloaded from the slow cooling cars by an overhead magnetic crane. Here the rails are set on the bed with their heads up and the heads are inspected. To facilitate inspection of the web and flange and expose the identification marking on the web, the rail must be turned on its side. This is ordinarily done by gripping the web at the end of the rail with a pronged iron bar and turning it manually. This is a slow, dangerous and tiresome task requiring great physical strength on the part of the operator. Several means for turning the rails have been devised, but none to my knowledge have been successful, one of the reasons for the failure being that the rails are not straight when they come out of the slow cooling cars.

It is also desirable to turn the rails on the hot beds during the cooling of the rails. My device is suitable for this purpose, but it is desirable to use more than one such device in order that the rails may be turned often enough to secure uniform cooling and thus compensate for the tendency of the hot rails to bend when cooled on their sides. In this installation my rail turning device may be used to turn the rails from side to side or from the side to the base.

It is an object of my invention to provide a device for mechanically turning and moving rails or like objects, such as beams or slabs.

This and other objects will be more apparent after referring to the following specification and attached drawings in which:

Figure 1 is a plan view of the transfer bed and the rerailer;

Figure 2 is a side elevation of Figure 1;

Figure 3 is an enlarged plan view of the rail turning carriage;

Figure 4 is an enlarged side elevation of the carriage taken on line IV—IV of Figure 1;

Figure 5 is an enlarged side elevation similar to Figure 4, but showing the rail being turned;

Figure 6 is an enlarged plan view of the skid; and

Figure 7 is a side elevation of Figure 6.

Referring more particularly to the drawings, the reference numeral 2 indicates the loading end of an inspection table on which the head of the rails are facing upwardly. The web and the flange of the rails are inspected on another section 4 separated from the section 2. The loading end 2 is provided with spaced apart supports 6

2

for supporting the rails transversely of their direction of movement. As best shown in Figures 6 and 7, each of the supports 6 consists of a pair of spaced apart angles 8 with a skid bar 10 therebetween, which is supported on a pivot pin 12 at the loading end of the support. The discharge ends of the angles 8 are provided with a plurality of holes 14 while similar holes 16 are arranged at various elevations in the bar 10. A pin 18 passing through a set of the holes 14 and 16 determines the height of the discharge end of the skid bar. The skid bar 10 is provided with a stop 19 at its rear end which prevents the rails from falling off that end. Section 4 of the inspection table is provided with skid rails 20. An inclined skid rail 22 extends from the top of skid rails 20 downwardly toward the skid bars 10. The supports 6, 20 and 22 are fastened in any suitable manner to the usual substructure 24. Mounted between the supports 6 is a pair of movable carriages 26. As best shown in Figures 3, 4 and 5, each of the carriages 26 is provided with four wheels 28 mounted on shafts 30. The frame 32 of the carriage is provided with a spacer 34 through which passes a bolt 36 to hold the parts of the frame together in spaced apart relationship. A bar 38 of the same length as spacer 34 is fastened to the parts of the frame in any suitable manner. A bar 40 fastened to the rear end of the carriage is screw threaded to receive screw 42 which carries a clevis 44. A pin 46 is fastened to the frame in front of the rear wheels 28. The ends of a cable 48 are fastened to the clevis 44 and the pin 46 to form an endless loop. The cable 48 extends around a drum at one end of the carriage travel and to a powered cable drive at the other end which is equipped with a variable speed motor to vary the speed of travel of the carriages on the rails 52. Pivotal mounted on a pin 54 at the rear end of the carriage is a dog 56. The plate 38 acts as a stop for the dog and prevents it from rotating rearwardly. The bottom of the dog is provided with a hole 58 and the carriage is provided with a similar hole 60 for a purpose which will appear later. Pivotal mounted on a pin 62 on each side of the front end of the carriage is a dog 64. Pawls 66 and 68 are pivotally mounted on each side of each dog for a purpose which will appear later. The top of the carriages 26 is below the level of the supports 6 and the skid bars 20 while the tapered skids 22 extend from the skid bars 20 to a point at or below the top of the carriage. The carriages 26 act in unison and if desired they could be connected to form a single carriage if the middle skid 20 is omitted.

In operation, the carriages 26 are moved to their rear position as shown in Figure 1 and several rails are deposited by an overhead magnet crane onto the adjustable skid bars 10. The dogs 56 are in their normal vertical position with the top thereof extending above the support 6. The

cable drive is then started to move the carriages forward with the dogs 56 contacting the rear rail. As the carriage moves forward the dogs push the rails along the support and off the front end thereof onto the carriages 26 as shown in Figure 5. The height of the skids 10 is adjusted for the size of the rail by passing a pin 18 through the selected openings 14 and 16. The traveling speed of the rails as they reach the end of the skid bars 10 must be the proper speed for the particular size rails being turned since at too high a speed the rails will not turn. The maximum traveling speed is easily determined by the operator. When the rails reach the end of the skid bars 10 they tumble over on their side the moment the center of gravity goes beyond the end of the skid rails onto the carriages 26. If the rails are on their sides they can be turned to their base or even to the other side. Normally the rails turn through an angle of about 90°. Since the turned rail is supported on the moving carriages 26, it is moved from the front of the support prior to the turning of the next succeeding rail. When the rails on the carriages reach a point along the tapered skids 22 at the same elevation as the top of the carriages 26, the weight of the rails is transferred from the carriages to the rails 20 of the inspection bed. From here the dogs 56 continue to push the rails toward the discharge end of the bed to a roller table (not shown). The length of the inspection bed may be such that a carload of rails may be accommodated thereon at one time. After the rails are inspected on section 4 of the inspection table, the dogs 56 are turned down so that they are below the top surface of the carriages. A pin is inserted through the holes 58 and 60 to hold the dog 56 on each carriage in its lowered position. In order that a single rail may be unloaded from the inspection table, if desired, the dogs 64 are used for unloading. In this operation the pawls 66 are turned to contact the adjacent dogs 64 and the pawls 68 are out of contact with the dogs. After the dogs 64 push a rail from the inspection table the carriages are moved backwardly under the rails and when the dogs 64 contact a rail they will be pivoted around the pins 62 so that they slide beneath the rails. When the carriages are stopped the dogs rotate in a clockwise direction and rise above the rails. Upon forward movement of the carriages the rails in front of dogs 64 are moved along the skids 20. In this manner any number of rails may be moved toward the roller table at one time. If, for any reason, it becomes desirable to move some of the rails on the inspection table back toward the loading end, pawls 66 are disengaged and pawls 68 are engaged with the dogs 64 to prevent counterclockwise movement of the dogs from a vertical position. When all the rails are removed from the section 4 or when it is desired to move and turn more rails from section 2, the carriages 26 are moved back to the original position and the pins removed from openings 58 and 60 to permit the dogs 56 to move to their vertical position.

The above described operation is then repeated.

While one embodiment of my invention has been shown and described, it will be apparent that other adaptations and modifications may be made without departing from the scope of the following claims.

I claim:

1. A device for turning and moving rails or the like comprising spaced apart supports for sup-

porting the rails transversely of their direction of movement, a movable carriage mounted adjacent said supports, means for moving said carriage at variable speeds longitudinally of said supports, the top of said carriage being below the top of said supports, the front end of said supports being substantially vertical, means for adjusting the distance between the top of the carriage and the top of the supports at the discharge end, means on said carriage for engaging the rails and pushing them off the front end of the support one at a time to turn them from one side to another, said carriage moving the turned rails from in front of the support prior to the turning of the next succeeding rail.

2. A device for turning and moving rails or the like comprising spaced apart supports for supporting the rails transversely of their direction of movement, a movable carriage mounted adjacent said supports, the top of said carriage being below the top of said supports, means on said carriage for engaging the rails and pushing them off the front end of the support to turn them from one side to another, said carriage moving the turned rails from in front of the support prior to the turning of the next succeeding rail, a second group of spaced apart supports for supporting the rails transversely of their direction of travel, said second supports being spaced longitudinally from said first supports in the direction of travel, the top of said carriage being below the top of the second supports, and an incline extending upwardly from the plane of the top of the carriage to the top of the second supports at the entry side thereof.

3. A device for turning and moving rails or the like comprising spaced apart supports for supporting the rails transversely of their direction of movement, a movable carriage mounted adjacent said supports, means for moving said carriage longitudinally of said supports, the top of said carriage being below the top of said supports, the front end of said supports being substantially vertical, means on the rear end of said carriage for engaging the rails as the carriage is moved toward the front end of said supports and pushing them off the front end of the support one at a time onto said carriage to turn them from one side to another.

4. A device for turning and moving rails or the like comprising spaced apart supports for supporting the rails transversely of their direction of movement, a movable carriage mounted adjacent said supports, the top of said carriage being below the top of said supports, means on the rear end of said carriage for engaging the rails and pushing them off the front end of the support onto said carriage to turn them from one side to another, a second group of spaced apart supports for supporting the rails transversely of their direction of travel, said second supports being spaced longitudinally from said first supports in the direction of travel, the top of said carriage being below the top of the second supports, and an incline extending upwardly from the plane of the top of the carriage to the top of the second supports at the entry side thereof.

5. A device for turning and moving rails or the like comprising spaced apart supports for supporting the rails transversely of their direction of movement, a movable carriage mounted adjacent said supports, means for moving said carriage at variable speeds longitudinally of said supports, the top of said carriage being below the top of said supports, the front end of said

supports being substantially vertical, means on the rear end of said carriage for engaging the rails as the carriage is moved toward the front end of said supports and pushing them off the front end of the support onto said carriage one at a time to turn them from one side to another, and means for adjusting the distance between the top of the carriage and the top of the supports at the discharge end.

6. A device for turning and moving rails or the like comprising spaced apart supports for supporting the rails transversely of their direction of movement, a movable carriage mounted adjacent said supports, the top of said carriage being below the top of said supports, means on the rear end of said carriage for engaging the rails and pushing them off the front end of the support onto said carriage to turn them from one side to another, means for adjusting the distance between the top of the carriage and the top of the supports at the discharge end, a second group of spaced apart supports for supporting the rails transversely of their direction of travel, said second supports being spaced longitudinally from said first supports in the direction of travel, the top of said carriage being below the top of the second supports, an incline extending upwardly from the plane of the top of the carriage to the top of the second supports at the entry side thereof.

7. A device for turning and moving rails or the like comprising spaced apart supports for supporting the rails transversely of their direction of movement, a movable carriage mounted adjacent said supports, means for moving said carriage longitudinally of said supports, the top of said carriage being below the top of said supports, the front end of said supports being substantially vertical, a plurality of pivotal dogs supported on the rear end of said carriage, and means for holding the dogs in position above the top of said supports so that they engage the rails and push them along the supports and off the front end thereof onto said carriage to turn them from one side to another as the carriage is moved toward the front end of said supports.

8. A device for turning and moving rails or the like comprising spaced apart supports for supporting the rails transversely of their direction of movement, a movable carriage mounted adjacent said supports, means for moving said carriage at variable speeds longitudinally of said supports, the top of said carriage being below the top of said supports, the front end of said supports being substantially vertical, a plurality of pivotal dogs supported on the rear end of said carriage, means for holding the dogs in position above the top of said supports so that they engage the rails and push them along the supports and off the front end thereof onto said carriage to turn them from one side to another as the carriage is moved toward the front end of said supports, and means for adjusting the distance between the top of the carriage and the top of the supports at the discharge end.

9. A device for turning and moving rails or the like comprising spaced apart supports for supporting the rails transversely of their direction of movement, a movable carriage mounted adjacent said supports, the top of said carriage being below the top of said supports, a plurality of pivotal dogs supported on the rear end of said carriage, means for holding the dogs in position above the top of said supports so that they engage the rails and push them along the supports and

off the front end thereof onto said carriage to turn them from one side to another, a second group of spaced apart supports for supporting the rails transversely of their direction of travel, said second supports being spaced longitudinally from said first supports in the direction of travel, the top of said carriage being below the top of the second supports, and an incline extending upwardly from the plane of the top of the carriage to the top of the second supports at the entry side thereof.

10. A device for turning and moving rails or the like comprising spaced apart supports for supporting the rails transversely of their direction of movement, a movable carriage mounted adjacent said supports, the top of said carriage being below the top of said supports, a plurality of pivotal dogs supported on the rear end of said carriage, means for holding the dogs in position above the top of said supports so that they engage the rails and push them along the supports and off the front end thereof onto said carriage to turn them from one side to another, means for adjusting the distance between the top of the carriage and the top of the supports at the discharge end, a second group of spaced apart supports for supporting the rails transversely of their direction of travel, said second supports being spaced longitudinally from said first supports in the direction of travel, the top of said carriage being below the top of the second supports, and an incline extending upwardly from the plane of the top of the carriage to the top of the second supports at the entry side thereof.

11. A device for turning and moving rails or the like comprising spaced apart supports for supporting the rails transversely of their direction of movement, a movable carriage mounted adjacent said supports, the top of said carriage being below the top of said supports, a plurality of pivotal dogs supported on the rear end of said carriage, means for holding the dogs in position above the top of said supports so that they engage the rails and push them along the supports and off the front end thereof onto said carriage to turn them from one side to another, means for adjusting the distance between the top of the carriage and the top of the supports at the discharge end, a second group of spaced apart supports for supporting the rails transversely of their direction of travel, said second supports being spaced longitudinally from said first supports in the direction of travel, the top of said carriage being below the top of the second supports, an incline extending upwardly from the plane of the top of the carriage to the top of the second supports at the entry side thereof, a plurality of pivotal dogs supported on the front end of said carriage, and means for holding the last named dogs in position above the top of said supports to engage the rails and push them along the supports in either direction.

GUSTAF WESTERHOLM.
